M. WILSON.
WINDOW GUARD.
APPLICATION FILED MAY 14, 1918.

1,356,953.

Patented Oct. 26, 1920.

INVENTOR

Michael Wilson
BY
Anthony Phelps Marr
ATTORNEY

UNITED STATES PATENT OFFICE.

MICHAEL WILSON, OF BROOKLYN, NEW YORK.

WINDOW-GUARD.

1,356,953.

Specification of Letters Patent. Patented Oct. 26, 1920.

Application filed May 14, 1918. Serial No. 234,425.

To all whom it may concern:

Be it known that I, MICHAEL WILSON, a citizen of the United States, and resident of the borough of Brooklyn, county of 5 Kings, city and State of New York, have invented certain new and useful Improvements in Window-Guards, of which the following is a specification.

The guard, the subject of this invention 10 is intended to operate with and in conjunction with a movable sash of a window and is further secured to the movable sash, but in such a manner that it may be readily released and removed when its operation and 15 the protection rendered by it are not desired.

A certain development of the principle 20 I employed and certain of the devices here shown are more fully shown and explained in my application dated July 11, 1917, under Serial No. 180,011. This present application shows a different development and one that may be preferred for certain reasons that will appear later, and in the specification which follows I will fully describe 25 the construction and operation of my device.

The following is what I consider a good 30 means of carrying out this invention and the accompanying drawings should be considered for a complete understanding of the description which follows:—

In the drawing,

Figure 1 shows a front elevation of my 35 device in operable position.

Fig. 2 is a side elevation of my device, the window and casing being shown in section.

Fig. 3 shows a modification of a part, 40 this figure is a fragmentary view.

Similar reference numerals indicate like parts in all of the figures where they appear.

At 1, I show a portion of a window casing and at 2, the sill is shown in section. 45 The upper sash and the glass secured therein is indicated at 3, and the lower sash and glass are indicated by the reference character 4.

50 I produce a longitudinal perforation in each side rail 5 and 6 of the lower sash. These perforations or holes need not extend entirely through the rails 5 and 6, but connect with the recess entering from the front 55 of the sash for a purpose that shall appear later.

Into each recess I insert a casting or fitting 7 and 8, and each casting or fitting is provided with a screw-threaded lug 9. The screw-threaded rod 10 enters from the top 60 through a perforation in each side rail and is by means of its screw-threads engaged in the lug 9.

Plates 11 and 12 recessed in the sash, 65 pass over the rods 10 and ball-nuts 13 and 14 are screw-threaded on the upper end of the rods and bear upon the plates 11 and 12.

It will be noted that the casting or fittings 8 extend outward from the sash and downward toward the sill of the window 70 and it will be further noted that each fitting 7 and 8 is provided with an eye 15 and 16.

From the eyes 15 and 16, I extend bar 17, each end of which is bent downward to be engaged in a second bar 18 and between 75 bars 17 and 18 I secure a plurality of fillers or upright rods which more or less completely fill the space between the downwardly turned ends of the bar 17.

The bars 18 and 19 and the downwardly 80 turned ends of the bar 17 enter the casing of the window and as they are secured to the movable sash 4, will be raised or lowered according as the sash 4 is moved.

For added security and to prevent a possibility of the removal of the ball-nuts 13 and 14 I may substitute for these nuts a cap 20 having a pivoted arm 21, adapted 85 to be rotated in the cap 20.

I insert a lock 22 into the sash of the 90 window and the eyes or loop 23 secured to or formed integral with the bar 21 enters the lock and is secured therein by the bolt of the lock 22.

As any type of lock 22 may be employed 95 I do not attempt to show the construction or operation of the lock.

With the construction herein shown the guard frame may be readily detached from the window when desired while at the same 100 time the location of the accessible members 13 and 14 of the attaching means of the frame at the top of the sash prevents an intruder from reaching the same by inserting his hand under the sash and through 105 the bars of the frame.

It will be noted that the fitting 8 is provided with a plate which covers the recess in the sash through which the lug 8 enters. This plate may be omitted as it performs 110 no important function and other modifications may be made within the scope of the

appended claims, without departing from the principle or sacrificing the advantages of this invention.

Having carefully and fully described my invention what I claim and desire to secure by Letters Patent is:—

1. A combination with a vertically slideable window sash having longitudinal bores extending substantially through the stiles 10 and horizontal openings near their lower ends, brackets, lugs on the brackets adapted to enter the horizontal openings, and having apertures adapted to register with said bores, a window guard secured to the brackets and rods extending into the bores and through the lugs.
- 15 2. A combination with a vertically slide-

able window sash having longitudinal bores extending substantially through the stiles and horizontal openings near their lower 20 ends, brackets, lugs on the brackets adapted to enter the horizontal openings, said lugs having threaded openings therein for aligning with the bores, and screw threaded rods extending through the bores and into the 25 threaded openings in the lugs.

Signed at New York city, in the county and State of New York, this 4th day of May, 1918.

MICHAEL WILSON.
